Arthur L. Lee, Columbus, Ohio, assignor to Consolidation Coal Company, Pittsburgh, Pa., a corporation of Pennsylvania

Filed Dec. 16, 1959, Ser. No. 859,882

30 Claims. (Cl. 255—47)

This invention relates to mining machines and more particularly to a drilling machine especially designed for use in underground mines or tunnels for drilling holes at various locations in the mine or tunnel walls and roof.

This application is a continuation-in-part of my co-pending applications Serial Number 659,843, filed May 17, 1957 and Serial Number 579,254, filed April 19, 1956. Application Serial Number 659,843 is a continuation-in-part of application Serial Number 169,752, filed June 22, 1950, now abandoned and application Serial Number 579,254 is a division of application Serial Number 169,752, filed June 22, 1950, now abandoned.

In conventional mining drills of the mobile type the drilling tools are usually mounted on adjustable supporting structures such as swingable booms. As a result of the substantial overhang of the boom structure in front of the base, considerable vibration is set up within the machine during the hole drilling operation. The present invention contemplates improvements over such known types of drilling machines in that the drill function is effected by a unitary self-contained machine. There is also included a novel guiding and supporting structure for a drilling tool wherein the drill guide frame is firmly held against the working face during the drilling operation thereby minimizing vibration and rendering the entire machine relatively steady. The machine of the present invention is flexible in operation having a wide range of adjustment and is relatively simple and rugged in design, and well adapted for its intended use.

An object of the present invention is to provide an improved supporting and guiding structure for a work supporting element and improved feeding and adjusting means therefor.

Yet another object is to provide an improved adjustable support for a drilling implement including a guide member for the drilling implement which is firmly held against the working face during the drilling operation to thereby hold the supporting structure steady.

A still further object is to provide improved means for feeding the drilling implement toward the work and for constantly urging the drill guiding frame against the face of the work during the drilling operation.

Yet another object is to provide an improved drill guiding frame along which a drill carriage is mounted for movement back and forth with respect to the work.

Still another object is to provide an improved driving means for a drilling tool and improved means for guiding the drilling tool during the drive thereof.

A further object is to provide an improved mining machine having improved fluid operated and adjusted supporting and guiding elements and embodying an improved fluid system.

Another object is to provide a means to propel the intermediate centralizer back and forth along the guide member.

Yet another object is to provide an improved mining machine having novel arrangements and combinations of parts.

These and other objects and advantages of the invention will, however, hereinafter more fully appear.

In the accompanying drawings to be taken as part of this specification, I have clearly and fully illustrated two embodiments of my invention, in which drawings:

5 Figure 1 is a diagrammatic side view of embodiment I showing the drilling implement comprising the supporting structure and guide frame mounted on a boom structure of a mobile mining machine and showing in dotted lines various positions of adjustment of the drilling implement.

Figure 44 is a vertical section similar to Figure 35 illustrating the modified form of the adjustable intermediate centralizer.

Figure 45 is a schematic perspective view similar to Figure 39 and illustrating the chain and sprocket driving connections for the extensible guide member, drill carriage and adjustable intermediate centralizer. The drill carriage and adjustable intermediate centralizer appear at various positions of adjustment relative to the guide member and are shown in dotted line in these adjusted positions.

Figure 46 is a view in central longitudinal vertical section similar to Figure 21 illustrating the adjustable intermediate centralizer.

EMBODIMENT I

As shown in Figure 1 the drill assembly generally designated by the numeral 1 may be carried by a mobile self-propelled mining machine or carriage 2 having a swiveled support 3 at its forward end and on which an adjustable supporting structure generally designated 4 is pivotally mounted to swing in vertical plane relative to the swiveled support 3 and to swing in horizontal planes with the swiveled support 3 relative to the carriage 2. The adjustable supporting structure 4 includes an elongated boom or arm 5 having a swiveled supporting yoke 6 at its outer extremity (Figure 2).

4

The yoke 6 has forwardly and outwardly projecting arms 7 which at their outer extremities pivotally engage transverse pivot pins 8 supported by brackets 9 secured to the outer sides of the elongated frame-like supporting member hereinafter referred to as a supporting frame 10.

The supporting frame 10 may be provided with fluid cylinders 11 as shown in Figures 2 and 3. The fluid cylinders 11 are pivotally connected at 12 to brackets 13 secured to the opposite sides of the supporting frame 10 rearwardly of the pivotal mounting of the supporting frame on the yoke arms 7, and these cylinders contain reciprocal pistons 14 (Figure 2) having forwardly projecting rods 15 pivotally connected at 16 to the rear sides of the yoke arms 7. Thus, when fluid under pressure is properly supplied to the cylinders, the supporting frame 10 may be adjusted angularly or tilted about its pivotal mounting on the yoke arms 7 and when fluid is trapped in these cylinders the supporting frame 10 may be rigidly held in its adjusted position.

20 The supporting frame 10 has longitudinal guiding means in which an elongated frame-like guide member hereinafter referred to as guide frame 17 (Figures 3, 4 and 8) is slidably guided for longitudinal movement back and forth with respect to the supporting frame 10, as 25 later described more in detail. The supporting frame 10 comprises beam like side members 18 (Figures 3, 8 and 12) to which the brackets 9 are secured. The side members 18 are rigidly secured in parallel spaced relation by front and rear tubular cross connecting members 19 and 30 (Figures 2, 4 and 5) secured to the ends of the side members 18 likewise as by welding. This assembly provides a rigid, unitary, supporting frame structure 10 along which the sliding guide frame 17 may move.

The guiding means between the support and guide frames 10 and 17 comprises a series of longitudinally spaced guide blocks 21 (Figures 2, 5, 8 and 12) rigidly secured as by rivets 22 to parallel side frames 23 of the sliding guide frame 17. These guide blocks 21 are slidably engaged in longitudinal guideways in the form of guiding slots 24 (Figures 8 and 12) formed in the supporting frame side members 18. The side members 18 are strengthened by reinforcing webs 25 spaced at intervals along their length and these webs are cut away at 26 to clear the sliding guide blocks as shown in Figure 12.

45 The rear cross connecting member 20 has a bracket 29 secured thereto (Figure 4). A pin 28 is carried by the bracket 29 and has a fluid adjusting cylinder 30 connected thereto at 27. The fluid adjusting cylinder 30 extends longitudinally beneath the supporting frame 10 and reciprocable in this cylinder is a piston 31 having a forwardly projecting piston rod 32 carrying a pulley or sheave block 33 at its forward end. A rear cable 34 and a front cable 35 each have their intermediate portions passing around the pulleys on the block 33. The rear cable 34 is secured at one end to the rear end of the supporting frame 10 at 36 and the front cable 35 is secured at one end to the front end of the supporting frame 10 at 37. The other end of the rear cable 34 is secured to a projecting lug 38 located adjacent the rear end of the sliding guide frame 17. The other end of the front cable 35 is secured to a lug 39 projecting from an intermediate portion of the sliding guide frame 17. Thus, when fluid under pressure is properly supplied to the adjusting cylinder 30 the piston may be actuated

60 to move the sliding guide frame 17 along its guideways relative to the supporting frame 10 through a distance substantially twice the length of the working stroke of the piston. During the drilling operation fluid under pressure may be vented from the front end of the cylinder 30 with a restricted flow, in a manner to be later described, so that the sliding frame 17 is constantly urged in a forward direction with respect to the supporting frame 10.

65 The sliding guide frame 17 has its parallel side frame portion 23 rigidly secured in parallel spaced relation at

its front and rear ends by a front cross frame 40 (Figure 4) and a rear cross frame 41. The front cross frame 40 is rigidly detachably secured to the forward ends of the side frame portions 23 as by screws (Figures 13 and 14) while the rear cross frame 41 is desirably rigidly secured to the side portions as by welding, as shown in Figures 9 and 10. Thus, a rigid unitary sliding guide frame is provided which may slide back and forth along its guideways relative to the supporting frame 16, and this sliding frame 17 in turn provides parallel longitudinal guideways 42 (Figures 8 and 12) which slidably receive the lateral guide portions 43 of a sliding cross head or carriage 44.

Mounted on depending brackets 45 and 46 (Figures 4, 5, 7 and 8) rigidly secured to the guide frame parallel side portions 23 are conventional hydraulic motors 47 and 48. The hydraulic motors 47 and 48 are operable in both directions, that is, they are reversible type motors.

The power shaft of the hydraulic motor 48 drives a worm gear 49 (see Figure 7) meshing with a worm wheel 50 secured to a transverse shaft 51 herein suitably journaled in bearings supported by the depending brackets 45 and 46. Secured to the projecting ends of the cross shaft 51 are chain sprockets 52 which engage the intermediate portions of parallel feed chains 53 which are guided with respect to the drive sprockets by parallel idler sprockets 54 (see Figure 4). The idler sprockets 54 are suitably supported within the depending brackets 45 and 46. The parallel feed chains 53 extend forwardly and rearwardly with respect to the idler sprockets 54 longitudinally within the sliding frame side portions 23 and pass around a pair of guide sprockets 55 each journaled on cross shafts 56. The cross shafts 56 are supported within the side of the front and rear cross frames 40 and 41 of the sliding guide frames 17 as shown in Figure 10. The parallel feed chains 53 are secured at their ends 57 to eye bolts 58 (Figure 4) which in turn are secured to the sliding cross head or carriage 44. Adjustable turnbuckle devices 59 are threadedly connected within the eye bolts 58 for effective relative adjustment thereof so that the tension of the chain sections may be properly adjusted. Thus, by properly operating the hydraulic motor 48, the sliding cross head or carriage 44 may be moved back and forth along its guideway 42 relative to the sliding guide frame 17.

The hydraulic motor 47 (Figures 4 and 8) has its power shaft connected by a universal drive shafting 60 which in turn is connected to and drives a longitudinally extending shaft 61 (Figure 16) journaled in bearings suitably supported within the front cross frame 49. Keyed to and driven by the shaft 61 is a spur gear 62 meshing with a spur gear 63. The spur gear 63 is journaled in bearings suitably supported within the front cross frame 40. A longitudinally extending splined shaft 64 is keyed to and driven by the gear 63. The shaft 64 extends longitudinally within the sliding frame 17 and is supported at its forward end within the hub of the gear 63 and at its rearward end within a bearing 65 (Figure 17). The bearing 65 is mounted in a bearing support 66 carried by the rear cross frame member 41.

A spur gear 67 (Figure 15) having its hub journaled in bearings supported by the carriage or sliding cross head 44, has sliding splined engagement with the longitudinally splined shaft 64. The spur gear 67, as later explained, rotates the rotary auger portion of the drilling implement. In order that this elongated longitudinally splined shaft 64 may be automatically maintained centered within limits with respect to the spur gears 63 and 67, the bearing support 66 has a radial flange 68 (see Figure 17). The radial flange 68 is frictionally engaged at its front and rear faces by annular friction plates or discs 69 which are tightly and yieldingly held in frictional contact with the radial flange 68 by a rubber like annulus or spring member 70. The spring member 70

is seated against a rear cap 71 secured as by screws to the rear end of the rear cross frame 41. Thus, the bearing support flange 68 may have limited lateral sliding movement with respect to the friction plates 69 while 5 adequately frictionally supported in position. Thus, in effect, a "floating" or yieldable support is provided for the rear shaft bearing.

The sliding spur gear 67 (Figure 15) on the sliding cross head or carriage 44 meshes with and drives a spur gear 72 secured to a sleeve 73 journaled in bearings supported by the sliding cross head or carriage 44. A releasable adapter member 74 is fitted into the cylindrical bore of the sleeve 73 and has a socket 75 for the reception of the shank end of an auger drill or rotary drilling implement 76 which carries a conventional rotary drilling bit 77 (Figures 3 and 4) at its front end. A manually operable spring pressed latch 78 has a portion extending through a side opening 79 in the adapter member 74 (Figure 15) and engages the steel shank for 10 releasably locking the shank in the socket. The adapter member 74 is releasably locked in position within the drive sleeve 73 and has a rearwardly opening central 15 recess 80 in which levers 81 are arranged with their inner ends loosely pivotally mounted on pivot pins 82 supported by the adapter member 74. The outer portions of these levers are pivotally connected by pivot pins 83 (Figure 15) to locking pins or plungers 84 20 slidingly guided in radial bores 85. Radial bores 85 are located in the rearward portion of the adapter member 74. The locking pins 84 extend through the radial bores 85 and are receivable in aligned radial openings 86 in the drive sleeve member 73. A coil spring 87 is arranged between the levers 81 for constantly urging the same apart to maintain the locking pins 84 in the 25 sleeve openings 86, as shown in Figure 15. These levers have rearward handle portions (not shown) whereby the levers may be manually pressed together against the action of the spring 87 to withdraw the locking pins 84 from the sleeve openings 86, thereby permitting a rearward axial withdrawal of the adapter member 74 from the bore of the drive sleeve 73.

Although not shown a keeper means may be provided on the rear cross frame 41 to lock the adapter member 74 thereto. Thus, when the adapter member 74 is 45 locked in its retracted position against the rear cross frame 41 the sliding cross head or carriage 44 may be advanced along the guideways of the sliding frame 17 relative to the then stationary auger drill steel. In this 50 manner the sliding cross head or carriage 44 may be utilized for purposes other than the advancing of the drill steel.

As shown in Figure 3 the auger drill steel or drilling auger 76 extends lengthwise of the sliding frame 17 through the front cross frame 40. In doing so the drilling auger 76 passes forwardly through a guide bushing 88 (Figure 16). The guide bushing 88 provides an inner cylindrical bearing surface with which the outer peripheries of the auger drill steel spiral vanes may have sliding supported engagement. The guide bushing 60 88 is secured in a rubber like sleeve 89 which in turn is secured within the outer sleeve 90. The outer sleeve 90 is supported within the bore of a tubular shaft 91 journaled in bearings that are suitably supported within the front cross frame 40 of the sliding guide frame 17. 65 Secured to the tubular shaft 91 intermediate its bearings is a spur gear 92 which meshes with and is driven by the spur gear 63. The guide bushing 88 may thus be driven through the spur gears 62, 63, and 92 at the same angular speed as the speed of rotation of the drive sleeve 73 and, consequently, at the same angular speed as the auger drill steel so that no relative rotative movement between the guide bushing and the auger steel may occur. Thus, excessive wear of the parts is avoided. The rubber bushing 89 which surrounds and supports the guide bushing 88 enables slight freedom of lateral

movement of the bushing 88 and thereby tends to reduce shock. Under certain conditions the rubber sleeve 89 may be eliminated and the guide bushing 88 may be supported directly within the metallic outer sleeve 90. Thus with the above described assembly, the hydraulic motor 47 drives the auger drill steel 76 through the splined shaft 64, spur gear 67 and spur gear 72. Due to the splined shaft 64 and the sliding spur gear 67 the auger drill steel 76 can be driven irrespective of the position of the sliding cross head or carriage 44 along the guideways on the sliding guide frame 17.

The sliding guide frame 17, as previously mentioned, is constantly urged in a forward direction during the drilling operation by the fluid adjusting cylinder 30 and the cables 34 and 35 (Figures 4, 5 and 6). The sliding guide frame front top frame 40 carries abutment engaging elements in the form of forwardly projecting pins 93 at its opposite sides (see Figures 2, 3 and 6). The pins 93 project in advance of the drill bit 77 when the auger steel is fully retracted on the guide frame 17, and have pointed front ends 94 engageable with the face of the work, such as the walls, roof or working face of a mine or tunnel.

The auger drill steel 76 when positioned in the socket 75 of cross head 44 has its diametrical axis below the guide frame side inturned upper end portions 23a. The relative position of the socket 75 and the guide frame side inturned upper end portions 23a is illustrated in Figure 12. Thus the auger drill steel 76 extends longitudinally down between the parallel side frames 23 of the sliding guide frame 17. This assembly provides a rigid base structure for the auger drill steel so that the forces exerted when drilling are more evenly distributed over the remainder of the drilling structure.

Now referring to the hydraulic fluid system shown diagrammatically in Figure 18 the pump 95 has its suction side connected by conduit 96 to a fluid tank or reservoir 97 which desirably contains a liquid such as a light oil. The discharge side of the pump 95 is connected by a conduit 98 to a manually operable valve device 99. Leading from the valve device 99 is a supply conduit 100 which is connected to a conventional variable volume control device 101. A supply conduit 102 leads from the conduit 100 in front of the variable volume control device 101 to a manually operable valve device 103. Leading from the valve device 103 are supply and exhaust conduits 104 and 105 which are connected respectively to the inlet and discharge sides of the hydraulic drill motor 47. Also leading from the manually operable control device 103 is a return conduit 106 which is connected back to the tank or reservoir 97. A conduit 107 connects the variable volume control device 101 to the return conduit 106. Also leading from the variable volume control device 101 is a return conduit 108 which connects to the return conduit 106. A drain conduit 109 extends from the motor 47 to the return conduit 108.

Leading from the supply conduit 100 is a branch supply conduit 110 containing a pressure regulator and connected to a conventional manually operable control valve device 111. Supply and exhaust conduits 112 and 113 lead from the valve device 111 to the inlet and discharge sides of the reversible feeding motor 48. Also, leading from the valve device 111 is a return conduit 114 connected to the return conduit 106.

The conduits 112 and 113 leading from the feeding motor 48 are connected by conduits 115 and 116 respectively to the opposite ends of the fluid cylinder 30 for the sliding guide frame 17 and the conduit 115 contains a check valve 117 which permits fluid flow through the conduit 115 from the conduit 112 but prevents reverse flow. The conduit 116 contains a restricted orifice device 118 which permits a restricted flow of fluid from the front end of the cylinder 30 through the conduit 116 to the conduit 113 so that when the motor 48 is operating

to effect a forward speed of the sliding frame 17 fluid is slowly vented from the front end of the cylinder 30 through the restricted orifice device 118. A manually operable valve device 120 has its supply and exhaust conduits 122 and 124 connected to conduits 96 and 106. The valve device 120 is connected by conduits 126 and 128 to the conduits 115 and 116 respectively leading to the opposite ends of the adjusting cylinder 30. The valve device 120 permits the adjustment of the guide frame 17 while the feeding motor 48 is deenergized.

Operation

The general mode of operation of the drilling implement may be as follows.

The drill assembly 1 is arranged on a boom structure as shown in Figure 1 and the mobile base or carriage 2 is advanced until the working place is reached. Then the drill assembly 1 is positioned in its desired location by adjustment of the swiveled support 3, adjustable supporting structure 4 and boom 5. When the drill assembly 1 is adjacent the working face, the guide frame 17 is adjusted and brought into position by operating the valve device 120 to move the guide frame 17 relative to the supporting frame 10. The guide frame 17 is moved forwardly so that the pins 93 are against the working face. This is accomplished by a separate fluid supply means 126 or 128 to the adjusting cylinder 30 and the valve device 120 which independently moves the sliding carriage 17 irrespective of operation of the remainder of the system.

The control valve device 99 is then operated to effect fluid supply from the pump 95 through the conduit 100 to the control valve device 103. The valve device 103 may be positioned to open the fluid supply through the conduit 104 to the drill rotating motor 47 to effect rapid rotation of the auger drill steel and drill bit. The control valve device 111 is then operated to effect fluid supply to the feeding motor 48 to thereby feed the auger drill steel 76 forwardly toward the working face and to hold the drill bit 77 against the hole bottom as the hole deepens. During running of the feed motor 48 fluid flows through the conduit 115 past the check valve 117 to the rear end of the adjusting cylinder 30 and concurrently fluid is vented in restricted quantity from the front end of the adjusting cylinder 30 through the conduit 116 past the restricted orifice device 118 so that the pressure acting on the rear pressure area of the feed piston urges the guide frame 17 forwardly. As a result, during the forward feeding operation of the auger 76, the sliding guide frame 17 and the abutment pins 93 are constantly urged against the working face so that the rapidly rotating drill steel 76 is held steady during the drilling operation. The valve device 111 may be positioned to effect reversal of the feeding motor 48 to thereby retract the outer drill steel from the work. After the drilling operation is complete valve device 120 is actuated to reverse the piston of the adjusting cylinder 30 and retract the guide frame 17.

EMBODIMENT II

Arrangement of the outer tubular supporting structure on the adjustable boom structure

In the invention shown in Figures 19 to 40 inclusive, the supporting and guiding structure of the drill which, in the present instance is of a relatively compact, tubular, telescopic construction, may be mounted on an adjustable boom structure. The projecting arms 95a of the swiveled yoke frame 79a at their outer ends pivotally engage transverse pivot pins 300 (Figures 20 and 27) fitted in bores 301 formed in trunnion members 302 secured as by welding to the rearward portion of a tubular outer casing or supporting member 303. The pivot pins are detachably secured in the trunnion bores as by bolts 304.

A fluid cylinder 305 (Figure 20) extends between the yoke frame 79a and the outer casing 303 and is pivotally connected at its rear end at 306 to lugs projecting from the base of the yoke frame 79a. Reciprocable in this cylinder is a piston 307 having its piston rod 308 projecting forwardly from the cylinder 305 and pivotally connected at 309 at its outer end to a bracket 310 secured as by welding to the tubular supporting member or outer casing 303 at a point in advance of the pivotal mounting of the outer casing 303 on the yoke frame 79a, as is clearly shown in Figure 20. When fluid under pressure is properly supplied to cylinder 305 the tubular casing 303 may be swung or tilted in a plane in one direction or the other about its pivotal connection to the yoke frame, and by trapping fluid in the cylinder 305 the outer casing 303 may be rigidly held in its adjusted position.

Arrangement of the tubular drill guide structure within the outer tubular supporting structure

Telescopically arranged within the outer tubular casing or supporting member 303 is an elongated inner drill guide member 311 likewise of cylindrical tubular form and desirably having its outer periphery spaced from the inner wall of the outer casing bore (Figure 21). The inner wall of the supporting member 303 provides a guideway for the elongated drill guide member 311. The under side of the outer casing 303 is longitudinally slotted at 312 (Figure 27) along its length. A housing 313 is secured to the adjacent side of the elongated inner tubular supporting member 311 substantially along the entire length thereof. The housing 313 projects outwardly through the outer casing slot 312. The housing 313 forms an elongated chamber 314 of generally rectangular cross section. The under side of the inner tubular guide member 311 is longitudinally slotted at 315 (Figures 27 and 28) with the slot connecting the interior of the tubular guide member 311 with the chamber 314 as is shown in Figure 27.

The trunnions 302 and the outer walls of the supporting member 303 have parallel transverse plates or flanges 316 secured thereto as by welding and also secured as by welding to the exterior of the outer casing 303 at a point spaced forwardly with respect to the flanges 316 is a flange 317 (Figure 20). Secured as by welding to the spaced flanges 316 and 317 at the opposite ends of the outer casing 303 are radial brackets or lugs 318 which are also welded to the outer casing 303. The lugs 318 provide radial recesses 319 at the upper side of the casing 303 and radial recesses 320 at the under side of the casing 303 as viewed in Figure 27. Bearing rollers 321 are arranged in both the recesses 319 and 320 and project through suitable openings (Figures 27 and 30) in the outer casing 303 into engagement with the outer periphery of the inner tubular guide member 311 at radially located and longitudinally spaced points. With this arrangement the inner tubular guide member 311 is firmly supported within the outer casing or supporting member 303 while the guide member 311 is free to move axially within the outer tubular casing 303.

The rollers 321 arranged in the recesses 320 on the under side of casing 303 are journaled on relatively inclined shafts 322 (Figure 27) supported within the lugs 318 while the rollers 321 in the recesses 319 on the upper portion of the casing 303 are journaled on shafts 323 mounted on levers 324 (Figure 29). The levers 324 are pivoted on relatively inclined transverse pivot pins 325 and are supported by spaced lugs. Set screws 326 are threaded within the outer ends of the levers 324 and are adjustable into engagement with the outer surface of the outer casing or supporting member 303. The set screws 326 by adjustment swing the levers 324 about their pivot pins 325 to adjust the position of the upper rollers 323 with respect to the casing 303 to thereby properly center

the inner casing or guide member 311 with respect to its roller bearing mounted within the outer casing 303.

Arrangement of the drill carriage within the tubular guide member

A drill carriage portion 332 of a drilling implement is guided for longitudinal movement within the guide member 311 (Figure 21). The inner wall of the guide member 311 provides a guideway for the drill carriage 332. The drill carriage 332 projects downwardly through the slot 315 into the chamber 314 for movement along the slot 315 as shown in Figure 25. The drill carriage 332 has arranged near its opposite ends relatively inclined shafts 333 (Figures 24, 25 and 26) on which bearing rollers 334 are journaled. The bearing rollers 334 engage the inner peripheral surfaces or bore walls of the guide member 311 at the opposite sides of the slot 315. A block member 335 is secured as by screws to the carriage 332. The block member 335 carries transverse shafts 336 near its opposite ends (Figure 24) on which bearing rollers 337 (Figure 25) are journaled. The bearing rollers 337 engage flattened surfaces at opposite sides of the slot 315 (Figures 25 and 26). The block 335 projects into the chamber 314 and the outer rollers 337 are located in chamber 314 and are enclosed within the housing 313. Screws 339 (Figures 25 and 26) threaded within the block 335 are engageable in annular grooves 340 in the shafts 336 to maintain the latter against axial displacement. Thus the bearing rollers 334 and 337 provide a rolling mounting for the drill carriage 332 whereby the latter may roll back and forth along a major portion of the length of the guide member 311 between the portions of the front and rear head frames 330 and 331.

The rear head frame 331 has an abutment surface 341 (Figure 24) which limits rearward movement of the drill carriage 332. The rear head frame 331 and the tubular guide member 311 are formed with openings 342 in the walls thereof to reduce weight and also, in certain instances, to obtain access to the internal structure.

Connection of auger drill steel in drill carriage

As illustrated in Figure 24 the drill carriage 332 has a longitudinal bore 343 coaxial with the guide member bore and arranged within the bore 343 is a bearing 344 in which an adapter member 345 is rotatably mounted. Front and rear seals 346 and 347 are provided at opposite ends of the bearing 344 to prevent access of dirt to the bearing and to prevent leakage of lubricant. Arranged in the bore of the adapter 345 is a shank 348 of an elongated auger drill steel or drilling auger 349. The adapter member 345 has a bore with a frusto-conical portion 350 which receives a frusto-conical portion 351 of the drill steel shank 348 (Figures 24). The rearward portion of the shank 348 is threaded at 352 and a nut 353 engages this threaded portion for drawing the drill steel shank 348 rearwardly within the bore and to hold the shank 348 firmly in position within the adapter 345. The adapter 345, seals 346 and 347 and bearing 344 are held in position within the drill carriage bore 343 by snap rings 354. The auger drill steel 349 extends forwardly centrally or axially within the inner tubular guide member 311 and projects forwardly outwardly through the front head frame 330 and carries at its front end a conventional rotary drill bit 355 (Figure 33).

Intermediate centralizer

As illustrated in Figures 21 and 35 there is a cylindrical guide member or intermediate centralizer 357 secured to the inner wall of the tubular guide member 311 by screws 356. The centralizer 357 has a central opening 358 which is connected to a lateral opening 359. The walls of the central opening 358 guide the intermediate portion of the auger drill steel 349 and limit bending stresses in the drill steel during the drilling operation. The central and lateral openings 358 and 359 are of such size and

shape as to permit the drill carriage 332 to pass through the intermediate centralizer 357 as the auger steel 349 is fed longitudinally relative to the guide member 311.

Means for propelling the guide member longitudinally relative to the supporting member

As illustrated in Figure 37 the outer casing or supporting member 303 has a frame portion 360 secured thereto and depending therefrom. A conventional reversible fluid motor 361 is mounted on the depending frame 360 and has its power shaft connected by a coupling 362 to a longitudinal shaft 363. The shaft 363 is journaled in bearings supported within a housing 364 which forms an integral part of the depending frame 360. Secured to the shaft 363 is a worm 365 meshing with a worm wheel 366 (see also Figure 28). The worm wheel 366 has its hub keyed to a transverse shaft 367 likewise journaled in bearings suitably supported within the housing 364. Keyed to the projecting outer end of the transverse shaft 367, exteriorly of the housing 364, is the hub of a chain drive sprocket 368. The drive sprocket 368 (Figure 36) engages the intermediate portion of a feed chain 369. The adjacent run of the feed chain 369 is guided for movement relative to the guide sprocket 368 by idler sprockets 370 journaled on parallel shafts 371 suitably supported within the frame 360 at opposite sides of the drive sprocket 368. The chain 369 extends longitudinally in opposite directions relative to the idler sprockets 370 along the outside of the housing 313 and passes around a rear chain sprocket 372 and a front chain sprocket 373 (Figures 36 and 37).

As shown in Figure 37 the front chain sprocket 373 is journaled on a shaft 374 carried by an adjustable bracket 375 guided in a longitudinal guideway 376 provided by a guide frame 377 secured as by welding to the side of the housing 313 on the tubular guide member 311. An adjusting device 378 is arranged between the sliding bracket 375 and a front lug on the front end of the guide frame 377 for adjusting the bracket longitudinally along its guideways to place the feed chain under proper tension. Screw and slot devices 379 are provided for rigidly clamping the bracket 375 in its adjusted position.

Propelling means for the drill carriage relative to the guide member

The rear sprocket 372 as illustrated in Figures 23 and 24 has its hub keyed to a transverse shaft 381. The transverse shaft 381 is journaled in bearings suitably supported within the guide member rear head frame 331. A large spur gear 382 is secured to and driven by the transverse shaft 381. The spur gear 382 meshes with a relatively small spur gear 383 secured to a parallel transverse shaft 384 that is likewise journaled in bearings supported within the guide member rear head frame 331. Due to the difference in tooth ratio (herein substantially 2 to 1) between the drive gear 382 and the driven gear 383, the shaft 384 is rotated at a speed substantially higher than (desirably twice) the speed of rotation of the shaft 381. Keyed to and driven by the driven shaft 384 is a chain drive sprocket 385. The chain drive sprocket 385 engages and drives a drill feed chain 386 which extends longitudinally within the chamber 314 of the housing 313 that is secured to the inner tubular guide member 311. The driving shaft 381 extends between the spaced runs of the drill feed chain 386.

As shown in Figures 21 and 24 the drill feed chain 386 is secured to the drill carriage 332 at its rear end at 387 by an adjustable eye bolt 388 which is arranged to adjust the tension of chain 386. The drill feed chain 386 extends forwardly within the chamber 314 and passes around a forwardly located guide sprocket 389 (Figures 21 and 33) that is carried by a transverse shaft 390 supported in the forward portion of the housing 313. Since the housing 313 is secured to and forms a

portion of the guide member 311 it may be stated that the front guide sprocket 318 is supported at the front end of the guide member 311. The other end of the drill feed chain 386 is secured to the drill carriage 332 at 391 (Figure 24) to a lug formed integral with the front portion of block 335 that is secured to and forms a portion of the drill carriage 332. Thus, when the motor 361 is operated the drill carriage 332 may be fed longitudinally along the inner tubular guide member 311 through the chain and sprocket connections.

Brake means for the drill carriage

Referring to Figures 22 and 23 there is shown a brake drum 395 whose hub is secured to the transverse drive shaft 381. The brake drum 395 is engaged by a contractile, split, brake band 396. This brake band has secured thereto midway between its ends a positioning lug 397 arranged between spaced stop lugs 398 on the same side of the rear head frame 331. The ends of the brake band 396 are associated with a bolt 399 and one of the band ends engages a head 400 of the bolt 399. A washer 401 is adjustably held in position by a nut 402 threaded on the bolt. Arranged between the washer 401 and the other end of the brake band 396 and surrounding the bolt 400 is a coil spring 403. Pivotal mounted on a cross pin 404 (Figure 22) supported within lugs 405 which are secured to the rear head frame 331 is a fluid cylinder 406 which contains a piston 407. A rod member 408 is arranged between the piston 407 and the spring-pressed end of the brake band 396. When fluid is supplied to the cylinder 406 beneath the piston 407 the latter is moved upwardly to raise the spring-engaged end of the band to thereby compress the spring and to release the braking pressure on the brake drum 395. When fluid is vented from the cylinder 406 the spring 403 automatically applies the brake.

Brake means for the guide member

As shown most clearly in Figure 28 pivotally mounted on the frame 360 at 410 on pivot pins are brake shoes or arms 411. Cross bolts 412 pass through openings in the outer end portions of the brake shoe arms 411. The bolts 412 have nuts 413 threaded on their opposite extremities and springs 414 are arranged between the nuts 413 and the brake shoe arms 411 to constantly urge the brake shoes into frictional braking engagement with the outer periphery of the axially movable inner tubular guide member 311. The side portions of the outer tubular supporting member 303 are provided with openings 415. Brake blocks 416, which are provided with suitable frictional braking material, are secured to the inner sides of the brake arms 411 and project inwardly through the openings 415 into contact with the inner tubular guide member 311. Pivots connected at 418 to a bracket 419 secured to the outer end of one of the brake shoe arms 411 is a link member 420 which passes through an opening in the lug 421 secured to the other brake shoe arm 411. The link 420 is pivotally connected at 422 to a bell crank lever 423 which in turn is pivotally mounted at 424 on the other brake shoe arm 411. Pivotally connected at 425 to a bracket that is an integral part of the frame 360 is a fluid cylinder 426 that contains a piston 427 and a piston rod 428 which extends upwardly from the cylinder 426. The free end of the piston rod 428 is pivotally connected at 429 to the projecting end of the bell crank lever 423. When a fluid under pressure is supplied through the cylinder 426 beneath the piston 427 the latter is moved upwardly swinging the bell crank lever 423 about its pivot 429 and through the pivotal mounting at 424 of the bell crank 423 on one of the brake shoe arms 411 and the pivotal connection of the link 420 with the brake shoe arm 411 at 422 the brake shoes 411 may be swung apart against the action of the springs 414. The movement of the brake shoe arms 411 by the force of the fluid in the

cylinder 426 releases the brake from the inner guide member 311. When fluid is vented from the cylinder 426 the coil spring 403 automatically applies the brake. The means for supplying fluid under pressure to the brake releasing cylinders 406 and 426 and the control to the brake releasing cylinders 406 and 426 and the control valve means therefor will later be described.

Operation of brake members

From the foregoing it is evident that when the brake band 396 is applied (Figures 22 and 23) the shaft 381 is held stationary thereby preventing circulation of the feed chain 369 relative to the sprockets 372 and 373 (Figure 36) and as a result when the motor 361 is operated the tubular inner guide member 311 may be adjusted axially in one direction or the other relative to the outer casing. When the brake band 396 is released (Figures 22 and 23) and the brake shoes 411 are applied (Figures 20 and 28) the inner tubular guide member 311 is held stationary with respect to the outer casing or supporting member 303 and when the motor 361 is operated the drill carriage 332 for the auger drill steel 349 may be moved longitudinally back and forth relative to the then stationary inner guide member 311.

A stop lug 435 is then secured as by screws to the outer surface of the tubular inner guide member 311 (Figures 19, 20 and 21). The stop lug 435 is engageable with the front end of the outer tubular supporting member 303 to limit rearward movement of the guide member 311. The forward movement of the guide member 311 is limited by engagement to the guide member rear head frame 331 with the rear end of the supporting member 303 (Figure 21).

Abutment means on guide member

The guide member front head frame 330 carries a pair of parallel, longitudinally extending abutment pins 436 at its opposite sides and these pins are fitted in longitudinal bores or bosses that are integral with the sides of the head frame 330 and are detachably held in the bores by screws 437 (Figure 32) engaging peripheral annular grooves 438 on the pins 436. The pins 436 have pointed front ends 439 engageable with the working face when the guide member 311 is moved forwardly.

Drive means to rotate the auger

Now referring to the driving means for the auger drill steel 349 it will be noted (Figures 34 and 36) that the supporting member 303 has a housing 440 secured thereto and extending downwardly therefrom. A hydraulic motor 441 is mounted on the housing 440 and has its power shaft keyed to a longitudinal shaft 442 (Figure 34). The shaft 442 is journaled in a front bearing supported within the housing 440 and formed on the shaft 442 is a spur gear 443. The spur gear 443 meshes with a spur gear 444 that is keyed to a tubular shaft 445. The tubular shaft is arranged parallel to the longitudinal shaft 442 and is likewise journaled in bearings supported within the housing 440. The tubular shaft 445 has internal keys 446 which are arranged to engage external splineways 447 on a tubular longitudinal shaft 448. The longitudinal splined tubular shaft 448 is telescopically arranged within the tubular shaft 445. The forward end of the splined shaft 448 carries internal keys 449 that engage external splineways 450 on an inner telescopic shaft 451. The shaft 451 is telescopically arranged within the tubular shaft 448. The shaft 451 has secured to its rearward portion a guide bushing 452 which provides a sliding guide for the rearward portion of the inner shaft 451 within the bore of the tubular shaft 448.

The shaft 451 extends forwardly along one side of the guide member housing 313 and is coupled at 453 to a longitudinal shaft 454 (Figure 33) journaled in bearings supported within the guide member front head frame 330. Keyed to the shaft 454 is a spur gear 455 that

is in meshing relation with an intermediate spur gear 456. The intermediate spur gear 456 is supported by a shaft 457 that is journaled in bearings within the head frame 330. The intermediate spur gear 456 meshes with 5 and drives a spur gear 458 that is in turn keyed to a tubular shaft or drive sleeve 459. The drive sleeve 459 is journaled in bearings that are likewise supported within the head frame 330.

Fitted in the bore of the drive sleeve 459 is a drive 10 bushing 460 (Figures 31 and 33) that is held against axial displacement by pins 461 fitted in aligned radial openings in the bushing or drive sleeve 459. The bushing 460 carries internal keys 462 engaging key slots 463 cut in the outer periphery of the auger drill steel spiral vanes 15 464. Thus as the drill steel 349 is moved axially through the bushing 460 it is rotated by the motor 441 through the telescopic shafting and spur gearing.

Drilling operation

20 When the inner tubular guide member 311 is moved up against the working face with the abutment pins 436 abutting the face, the brake band 396 is released and the brake shoes 411 are maintained released, with the drill bit 355 held against the work, so that when motors 441 25 and 361 are operated the drill bit is rapidly rotated and is fed forwardly to effect drilling of a hole. During the hole drilling operation the reaction of the drill bit due to resistance by penetration of the work during drilling acts back through the chain and sprocket connection 386, 385, 30 389, the gearing 383, 382 and the chain and sprocket connection 372, 369, 373 to thereby constantly urge and hold the drill guide member 311 forwardly against the working face. The chain, sprocket and gearing arrangement is schematically set forth in Figure 39. Due to the 35 gear ratio of the gears 383, 382 the pressure (say 1,000 lb.) tending to urge the drill guide member forwardly against the face is substantially twice the forward feeding pressure (say 500 lb.) of the drill bit.

The hydraulic fluid system

As shown diagrammatically in Figure 40 the fluid system of the invention may be associated with a large part of the fluid system of a vehicle and boom control. The fluid supply conduits 219 and 237 and the return conduits 45 225 and 227a may extend through a fluid swivel or coupling of a rotatable boom by which the yoke frame 79a may be swivelly supported. The supply conduit 219 leads to a variable volume control device 220 and through the supply conduit 221 to a manually operable control 50 valve device 222a. The return conduit 227 leads from the variable volume device 220 to the return conduit 225 which also has a connection with the valve device 222a. A fluid supply conduit 223a leads from the valve device 222a to the inlet side of the auger rotating motor 441, 55 and the discharge side of the auger rotating motor 441 is connected by the conduit 224 to the valve device 222a. Branching from the supply conduit 223a is a fluid conduit 465 connected to the brake cylinder 406 for supplying fluid to the latter to effect release of the brake band 60 396. Also leading from the motor 441 is the drain conduit 228 connected to the return conduit 227a.

Leading from the supply conduit 219 is a conduit 246a containing a pressure regulator PR and connected to a manually operable control valve device 247a. Leading 65 from the valve device 247a is a supply conduit 248a leading to the inlet side of the adjusting motor 361. The discharge side of the motor 361 is connected by a discharge conduit 249a to the control valve device 247a. Leading from the control valve device 247a is a return 70 conduit 250a connected to the return conduit 225. The conduits 248a and 249a are respectively connected by conduits 446 and 447 to a manually operable control valve device 468. A supply conduit 469 leads from this control valve device 468 to the fluid cylinder 426 of the 75 brake for the inner tubular guide member 311. A re-

turn conduit 470 leads from the control valve device 468 to the return conduit 250a. The control valve box 241 has its bore containing the control valve 243a connected by conduits 471 and 472 to the opposite ends of the tilt cylinder 305 for the supporting member 303.

Operation of the hydraulic system

From the foregoing it will be evident that when the drill motor 441 is operating to effect drilling, fluid flows through conduit 465 to the cylinder 406 to actuate the piston 407 and effect release of the brake band 396 from the brake drum on the sprocket shaft 381. When the feed motor 361 is operating fluid may be supplied through conduit 469 to effect release of the brake shoes 411 from the inner guide member 311. The control valve devices 222a and 468 may also be positioned to effect venting of the brake cylinders to effect application of the brakes by the brake loading springs. As above mentioned, during rotation and forward feeding of the drill bit during the hole drilling operation, both brakes are maintained released and the brakes are applied only during positioning or adjusting movements of the drill bit and the tubular guide member 311. Evidently, reversal of the feeding motor 361 may be effected by proper manipulation of the control valve device 247a so that the inner tubular guide member 311 may be retracted with respect to the outer casing or supporting member 303. By conventionally locating the control devices down on the boom, control of the drilling and feeding motors and the brakes may be effected even when the boom frame is swung upwardly with the drill guide member raised up in a relatively high position near the roof.

Timber setter adapter

The drill guide member front and rear head frames 330 and 331 have upstanding front and rear perforated flanges or lugs 475 (Figures 19, 20 and 25). A timber saddle 200 (Figure 38) may be secured to the perforated flanges 475 for mounting the saddle 200 on either of the head frames 330 or 331. Thus, the timber saddle in either of its locations may be adjusted longitudinally relative to the outer casing or supporting member 303 bodily with the movable inner frame or drill guide member 311 to thereby facilitate positioning of a timber with respect to the mine or tunnel roof. In Figure 38 a timber T is shown held up against the roof by the boom of a drilling machine with the timber T supported by the saddle 200 mounted on the drill guide member front head frame 330. The extended forward position of the drill guide member 311 and the timber saddle 200 are indicated in dotted lines in Figure 38. By locating the timber saddle 200 selectively on either head frame at the opposite ends of the adjustable drill guide member 311 a wide range of timber setting positions are obtainable thereby to avoid frequent maneuvering of the machine base during the timber setting operation. This modified timber setting structure is fully disclosed in divisional application Serial Number 313,407, now Patent #2,738,081. The boom of the machine may be swung horizontally relative to the base to increase the lateral range of the timber setting adjustment of the machine. The drill and timber saddle may be widely adjusted with respect to the machine base to enable a wide variation in the drilling and timber setting locations in the mine passageway or tunnel and the drill guide member is constantly held against the working face to steady the boom and the supporting and guiding structure during the drilling operation.

The adjustable intermediate centralizer

As illustrated in Figures 41 through 46 inclusive there is shown a modification of the intermediate centralizer for the drill steel. Throughout the remainder of this specification wherein the adjustable centralizer will be described, like numerals refer to like parts that have

been heretofore described in relation to Figures 19 through 40.

Figure 41, which is similar in many respects to Figure 23, illustrates an additional transverse shaft 500 which is interconnected to transverse drive shaft 381 by means of the gears 382 and 501. Thus as chain 369 drives shaft 381 the transverse shaft 500 is driven through gears 382 and 501 preferably at the same speed as the drive shaft 381 and at one-half the speed of driven shaft 384. Due to the arrangement of gears 501 and 383 relative to drive gear 382, the transverse shafts 384 and 500 rotate in the same direction. The transverse shaft 500 has a sprocket 502 secured thereto between the chains 369 and 386. Extending around and driven by sprocket 502 is a third chain 503. The chain 503 also extends around a front guide sprocket 504 (Figures 42, 43 and 46) which is secured to the transverse shaft 390. The transverse shaft 390 as previously described is rotatably secured to the drill guide member housing 313 and also carries the guide sprocket 389 thereon. The ends of chain 503 are secured to the adjustable intermediate centralizer 505 at 506 and 507 (Figure 46).

Figures 44 and 46 illustrate the construction of the intermediate centralizer 505. The intermediate centralizer 505 is cylindrical in shape and has a plurality of radially extending roller bearings 508 secured thereto. The bearings 508 are arranged to abut the inner portion of the drill guide member 311 so that the intermediate centralizer 505 is movable axially relative to the drill guide member 311. The intermediate centralizer 505 has a central aperture 509 through which the auger drill steel 349 extends. The auger steel spiral vanes 464 abut the inner wall of the intermediate centralizer aperture 509 so that the auger drill steel 349 is limited in bending due to the intermediate centralizer 505.

As shown in Figure 44 the intermediate centralizer 505 has a downwardly extending portion 510 which is offset to permit passage of chain 386 and extends downwardly to receive the ends of chain 503 at 506 and 507 (Figure 46).

The operation of the adjustable intermediate centralizer 505 is clearly illustrated in the schematic of Figure 45 wherein the various adjusted positions of the drill carriage 332 and the intermediate centralizer 505 are illustrated as the drill carriage 332 advances toward the working face. The arrows shown in Figure 45 illustrate the direction of motion of the drive chain 369, drive sprocket 372 and transverse drive shaft 381. The arrangement between gears 382, 383 and 501 and their relative ratios advances the drill carriage 332 twice the distance the adjustable intermediate centralizer is advanced, hence the intermediate centralizer always remains equidistant between the drill carriage 332 and the guide member front frame 330. In maintaining this intermediate position the centralizer 505 prevents substantial bowing or bending stress in the drill steel 349 and hence permits an increase in feeding velocity of the auger drill steel into the work.

SUMMARY

A tubular drill guide member 311 is telescopically carried within a tubular supporting member 303. A drive means is provided to move the drill guide member 311 axially relative to the supporting member 303. A drill carriage 332 having a drill steel 349 extending forwardly therefrom is telescopically carried within the drill guide member 311. A drive means is also provided to move the drill carriage 332 axially or longitudinally relative to the drill guide member 311. Thus, the drill carriage 332 is movable axially relative to the guide member 311 and its movement is independent of the relative position of the guide member 311 on the drill carriage 332. Also the drill guide member 311 is movable relative to the supporting member 303 and its movement is independent of the position of the drill carriage 332 within the guide member 311.

The drive means for the drill carriage 332 and the drive means for the drill guide member are arranged so that the guide member 311 is maintained in abutting relation with the working face as the drill carriage 332 and rotary auger 349 are advanced into the working face.

There is also provided an improved intermediate drill centralizer 505 illustrated in Figures 41-46 that is maintained equidistant between the advancing drill carriage 332 and the guide member head frame 330 to provide maximum support for the rotary auger 349 as it advances into the work.

According to the provisions of the patent statutes, I have explained the principle, preferred construction and mode of operation of my invention and have illustrated and described what I now consider to represent its best embodiments. However, I desire to have it understood that, within the scope of the appended claims, the invention may be practiced otherwise than as specifically illustrated and described.

I claim:

1. In a drilling machine the combination comprising an elongated supporting member having a longitudinal guideway, an elongated guide member having a longitudinal guideway substantially along its length, means for mounting said guide member for endwise guided movement in a longitudinal direction along said supporting member guideway, a drilling implement extending lengthwise of said guide member and guided for movement axially along said guide member guideway for endwise guided movement therein substantially within the lateral periphery of said guide member, abutment means at the front end of said guide member for engaging the face of the work to be drilled, power operated means for moving said guide member forwardly relative to said supporting member to bring said abutment means against the working face and for moving said drilling implement relative to said guide member, and means for constantly urging said abutment means forwardly to maintain said abutment means firmly against the working face during the advancement of said drilling implement.

2. In a drilling machine, the combination comprising an elongated supporting member having a longitudinal guideway, an elongated guide member having a longitudinal guideway substantially along its length, means for mounting said guide member for endwise guided movement in a longitudinal direction along said supporting member guideway, a drilling implement extending lengthwise of said guide member and guided for movement axially along said guide member guideway for endwise guided movement therein substantially within the lateral periphery of said guide member, abutment means at the front end of said guide member for engaging the face of the work to be drilled, and power operated means for moving said guide member forwardly relative to said supporting member to bring said abutment means against the working face and for moving said drilling implement relative to said guide member, said power operated means embodying means for constantly urging said guide member forwardly in order to maintain said abutment means firmly against the working face during the advancement of said drilling implement.

3. In a drilling machine the combination comprising a supporting member, a guide member carried by said supporting member and movable longitudinally relative to said supporting member, a drilling implement carried by said guide member and movable longitudinally relative to said guide member, abutment means at the front end of said guide member for engaging the face of the work to be drilled, guide means mounted on said guide member, a flexible element guided for circulation around said guide means so that said flexible element circulates relative to said guide member, means connecting said flexible element to said drilling implement so that upon circulation of said flexible element about said guide means said

drilling implement moves longitudinally relative to said guide member, means for moving said guide member forwardly relative to said supporting member to bring said abutment means against the working face and for circulating said flexible element around said guide means, and means for constantly urging said abutment means forwardly to maintain said abutment means firmly against the working face while said drilling implement moves forwardly relative to said guide member during the drilling operation.

4. In a drilling machine the combination comprising a supporting member, a guide member carried by said supporting member and movable longitudinally relative to said supporting member, a drilling implement carried by said guide member and movable longitudinally relative to said guide member, abutment means at the front end of said guide member for engaging the face of the work to be drilled, propelling means for said drilling implement operable to move said drilling implement longitudinally relative to said guide member, said propelling means including a motor mounted on said drilling machine, guide means mounted on said guide member, a flexible element guided for circulation around said guide means so that said flexible element circulates relative to said guide member, driving connections between said motor and said flexible element, means connecting said flexible element to said drilling implement so that upon circulation of said flexible element around said guide means said drilling implement moves longitudinally relative to said guide member, means for moving said guide member forwardly relative to said supporting member to bring said abutment means against the working face, and means for constantly urging said abutment means forwardly to maintain said abutment means firmly against the working face while said drilling implement moves forwardly relative to said guide member during the drilling operation.

5. In a drilling machine the combination comprising a supporting frame, a guide frame movable longitudinally on said supporting frame, a drilling implement carried by said guide frame and movable longitudinally thereon, said drilling implement mounted substantially within the lateral periphery of said guide frame, fluid operated means to propel said guide frame in its forward direction relative to said supporting frame, second fluid operated means to propel said drilling implement forwardly relative to said guide frame, a pump operable to supply fluid under pressure, a conduit circuit connecting said pump to said first and second fluid operated means so that upon energization of said pump both of said fluid operated means are subjected to fluid under pressure, said first and second fluid pressure operated means being constructed and arranged to effect application of a substantially greater forward urging pressure to said guide frame than the forward feeding pressure applied to said drilling implement so that said guide frame may be maintained in abutting relation with the working face during the drilling operation.

6. A drilling machine as set forth in claim 5 which includes a flow restrictor associated with the fluid outlet side of said first fluid operated means, said restrictor adapted to limit the rate of forward movement of said guide frame.

7. A drilling machine as set forth in claim 5 which includes means to advance and retract said guide frame relative to said supporting frame irrespective of movement of said drilling implement relative to said guide frame.

8. In a drilling machine, the combination comprising a supporting frame having elongated side portions in spaced parallel relation to each other and defining a longitudinal passageway therebetween, a guide frame having longitudinal side members with upper edge portions, transverse members rigidly securing said side members in spaced parallel relation to each other and defining a longitudinal guide way therebetween, said guide frame being slidably

carried by said supporting frame in said passageway between said supporting frame side portions, said guide frame being movable longitudinally relative to said supporting frame, a sliding auger receiving crosshead carried by said guide frame side members and positioned in said guide way between said guide frame side members, auger supporting means secured to said guide side members adjacent the front end of said guide frame, an auger secured at one end in said auger receiving crosshead and supported in said auger supporting means, said auger extending longitudinally in said guide way substantially below said guide side member upper edge portions, said auger and auger receiving crosshead being movable longitudinally relative to said guide frame in said guide way, and power operated means for moving said guide frame forwardly relative to said supporting frame while said auger receiving crosshead remains fixed relative to said guide frame and for feeding said auger receiving crosshead relative to said guide frame.

9. In a drilling machine, the combination comprising a supporting frame having elongated side portions in spaced parallel relation to each other and defining a longitudinal passageway therebetween, a guide frame having longitudinal side members with upper edge portions, transverse members rigidly securing said side members in spaced parallel relation to each other and defining a longitudinal guide way therebetween, said guide frame being slidably carried by said supporting frame in said passageway between said supporting frame side portions, said guide frame being movable longitudinally relative to said supporting frame, a sliding auger receiving crosshead carried by said guide frame side members and positioned in said guide way between said guide frame side members, auger supporting means secured to said guide side members adjacent the front end of said guide frame, a rotatable auger secured at one end in said auger receiving crosshead and supported in said auger supporting means, said auger extending longitudinally in said guide way substantially below said guide side member upper edge portions, said auger and auger receiving crosshead being movable longitudinally relative to said guide frame in said guide way, abutment means at the front end of said guide frame for engaging the face of the work to be drilled, and power operated means for moving said guide frame forwardly relative to said supporting frame to bring said abutment means against the working face while said auger receiving crosshead remains fixed relative to said guide frame and for feeding said auger receiving crosshead relative to said guide frame.

10. In a drilling machine, the combination comprising a supporting frame having elongated side portions in spaced parallel relation to each other and defining a longitudinal passageway therebetween, a guide frame having longitudinal side members with upper edge portions, transverse members rigidly securing said side members in spaced parallel relation to each other and defining a longitudinal guide way therebetween, said guide frame being slidably carried by said supporting frame in said passageway between said supporting frame side portions, said guide frame being movable longitudinally relative to said supporting frame, a sliding auger receiving crosshead carried by said guide frame side members and positioned in said guide way between said guide frame side members, auger supporting means secured to said guide side members adjacent the front end of said guide frame, a rotatable auger secured at one end in said auger receiving crosshead and supported in said auger supporting means, said auger extending longitudinally in said guide way substantially below said guide side member upper edge portions, said auger and auger receiving crosshead being movable longitudinally relative to said guide frame in said guide way, a pair of abutment pins extending longitudinally from the front end of said guide frame in spaced parallel relation to each other and on opposite sides of the path followed by said rotary auger, said pins having pointed ends adapted to engage the working face, power operated means for moving said guide frame forwardly relative to said supporting frame to bring said abutment pins against the working face while said auger receiving crosshead remains fixed relative to said guide frame and for feeding said auger receiving crosshead relative to said guide frame, and means to maintain said pins in abutting relation with said working face during the entire drilling operation.

11. In a drilling machine, the combination comprising a supporting frame having elongated side portions in spaced parallel relation to each other and defining a longitudinal passageway therebetween, a guide frame having longitudinal side members with upper edge portions, transverse members rigidly securing said side members in spaced parallel relation to each other and defining a longitudinal guide way therebetween, said guide frame being slidably carried by said supporting frame in said passageway between said supporting frame side portions, said guide frame being movable longitudinally relative to said supporting frame, a sliding auger receiving crosshead carried by said guide side members and positioned in said guide way between said guide side members, auger supporting means secured to said guide side members adjacent the front end of said guide frame, a rotatable auger secured at one end in said auger receiving crosshead and supported in said auger supporting means, said auger extending longitudinally in said guide way substantially below said guide side member upper edge portions, said auger and auger receiving crosshead being movable longitudinally relative to said guide frame in said guide way, a pair of abutment pins extending longitudinally from the front end of said guide frame in spaced parallel relation to each other and on opposite sides of the path followed by said rotary auger, said pins having pointed ends adapted to engage the working face, power operated means for moving said guide frame forwardly relative to said supporting frame to bring said abutment pins against the working face while said auger receiving crosshead remains fixed relative to said guide frame and for feeding said auger receiving crosshead relative to said guide frame.

12. In a drilling machine, the combination comprising a supporting frame, a guide frame movable longitudinally on said supporting frame, a drilling implement carried by said guide frame and movable longitudinally thereon, abutment means at the front end of said guide frame for engaging the face of the work to be drilled, a motor on said guide frame, a drive sprocket driven by said motor and also carried by said guide frame, a chain engaged by said drive sprocket and guided for circulation relative to said guide frame, guide sprockets on said guide frame for guiding said chain during its circulation, said drilling implement being connected to said chain so that upon circulation of said chain on said guide frame said drilling implement moves longitudinally relative to said guide frame, means associated with said motor for moving said guide frame forwardly relative to said supporting frame to bring said abutment means against the working face and for feeding said drilling implement relative to said guide frame, and means for constantly urging said abutment means forwardly to maintain said abutment means firmly against the working face during the feeding of said drilling implement.

13. In a drilling machine the combination comprising a guide frame having parallel side members, front and rear cross members extending transversely of said side members adjacent the respective side member end portions thereby maintaining said side members in spaced parallel relation to each other and forming a longitudinal guide way therebetween, a carriage traversable longitudinally within said guide way, an auger extending lengthwise in said guide way, said carriage having means to engage the shank end portion of said auger, gear means within said carriage operable upon movement to

rotate said auger, auger supporting means within said guide frame front cross member, splined shafting rotatably supported on said front and rear cross members, a motor mounted on said guide frame, driving connections between said motor and said splined shaft and between said splined shaft and said gear means, a chain attached to said carriage, guide sprockets on said guide frame, and means to circulate said chain about said guide sprockets to thereby move said carriage longitudinally in said guide way, said driving connections between said splined shaft and said gear means being arranged to rotate said gear means upon energization of said motor irrespective of the relative longitudinal position of said carriage in said guide frame guide way.

14. In a drilling machine, the combination comprising a supporting frame having elongated side portions in spaced parallel relation to each other and defining a longitudinal passageway therebetween, a guide frame having longitudinal side members, transverse members rigidly securing said side members in spaced parallel relation to each other and defining a longitudinal guide way therebetween, said guide frame being slidably carried by said supporting frame in said passageway between said supporting frame side portions, said guide frame being movable longitudinally relative to said supporting frame, a sliding auger receiving crosshead carried by said guide frame side members and positioned in said guide way between said guide frame side members, auger supporting means secured to said guide frame side members adjacent the front end of said guide frame, a rotatable auger secured at one end in said auger receiving crosshead and supported in said auger supporting means, said auger extending longitudinally in said guide way, gear means within said auger receiving crosshead operable upon movement to rotate said auger, splined shafting rotatably supported on said guide frame in spaced parallel relation to said auger, a motor mounted on said guide frame, driving connections between said motor and said splined shaft and between said splined shaft and said gear means, a chain attached to said auger receiving crosshead, guide sprockets on said guide frame, means to circulate said chain about said guide sprockets to thereby move said auger receiving crosshead longitudinally on said guide frame, said driving connections between said splined shaft and said gear means being arranged to rotate said gear means upon energization of said motor irrespective of the longitudinal position of said auger receiving crosshead in said guide frame guide way, abutment means at the front end of said guide frame for engaging the face of the work to be drilled, and means for moving said guide frame forwardly relative to said supporting frame to bring said abutment means against the working face, and means for constantly urging said abutment means forwardly to maintain said abutment means firmly against the working face during the feeding of said auger receiving crosshead.

15. In a drilling machine, the combination comprising a tubular supporting member, a tubular guide member telescopically carried within said tubular supporting member, a drilling implement carried with said tubular guide member and movable longitudinally along said guide member, abutment means at the front end of said guide member for engaging the face of the work to be drilled, and power operated means for moving said guide member forwardly relative to said supporting member to bring said abutment means against the working face and for feeding said drilling implement relative to said guide member, said power operated means embodying means for constantly urging said guide member forwardly to maintain said abutment means firmly against the working face during the feeding of said drilling implement.

16. A drilling machine as set forth in claim 15 wherein said drilling implement includes a rotary auger arranged coaxially with said tubular telescopic supporting member and guide member, and said rotary auger extends axially within said guide member.

17. In a drilling machine as set forth in claim 16 wherein in said abutment means comprises a pair of abutment pins extending longitudinally from the front end of said guide member in spaced parallel relation to each other and on opposite sides of the path followed by said rotary auger during the drilling operation, and having pointed ends adapted to engage the working face.

18. In a drilling machine as set forth in claim 15 wherein in said power operated means is operable to move said guide member longitudinally relative to said supporting member independently of the position of said drilling implement on said guide member.

19. In a drilling machine as set forth in claim 16 wherein in said rotary auger has spiral vanes, key slots cut in the periphery of said spiral vanes thereby providing a longitudinal splineway, and rotating means for said rotary auger comprising a rotatable drive bushing through which said rotary auger extends and is axially movable, said drive bushing carrying a key engaging the splineway provided by said key slots.

20. In a drilling machine the combination comprising a supporting member, a guide member carried by said supporting member and movable longitudinally relative to said supporting member, a drilling implement carried by said guide member within the lateral periphery of said guide member, said drilling implement being movable longitudinally relative to said guide member, propelling means arranged to move said guide member relative to said supporting member and said drilling implement relative to said guide member, drive means constructed and arranged to energize said propelling means to move said guide member longitudinally relative to said supporting member and to move said drilling implement longitudinally relative to said guide member, means connecting said propelling means to said drive means and means to maintain said drilling implement in a fixed position relative to said guide member while said guide member moves longitudinally relative to said supporting member.

21. In a drilling machine the combination comprising 40 a supporting member, a guide member carried by said supporting member and movable longitudinally relative to said supporting member, a drilling implement carried by said guide member and movable longitudinally relative to said guide member, a first pair of guide sprockets mounted on said guide member, a first endless chain guided for circulation about said first pair of guide sprockets, a second pair of guide sprockets mounted on said guide member, a second endless chain guided for circulation about said second pair of guide sprockets, 45 driving connections between one of said first pair of guide sprockets and one of said second pair of guide sprockets, said drilling implement being secured to one of said chains so that upon circulation of said chain about said respective guide sprockets said drilling implement moves longitudinally relative to said guide member, drive means 50 operatively connected to one of said chains and arranged through said driving connections between said sprockets to circulate both of said chains about their respective guide sprockets and means connected to said second endless chain and movable relative to said guide member upon actuation of said drive means.

22. In a machine of the character disclosed, the combination comprising a supporting member, a guide member mounted on said supporting member for longitudinal guided movement with respect thereto, a motor on said supporting member, a drive sprocket driven by said motor and also carried by said supporting member, a chain engaged by said drive sprocket and guided for circulation relative to said guide member, guide sprockets on said guide member for guiding said chain during its circulation, a drilling implement guided for movement longitudinally along said guide member, a second chain guided for circulation relative to said guide member, guide sprockets at the ends of said guide member for guiding said second mentioned chain for circulation, and a driv- 75

ing connection between one of said first mentioned guide sprockets and one of said second mentioned guide sprockets for driving the latter.

23. In a machine of the character disclosed, the combination comprising a supporting member, a guide member mounted on said supporting member for longitudinal guided movement with respect thereto, a motor on said supporting member, a drive sprocket driven by said motor and also carried by said supporting member, a first chain engaged by said drive sprocket and guided for circulation relative to said guide member, first guide sprockets on said guide member for guiding said first chain during its circulation, a drilling implement guided for movement longitudinally along said guide member, a second chain guided for circulation relative to said guide member, said second chain secured to said drilling implement, second guide sprockets on the ends of said guide frame and guiding said drilling implement relative to said guide member, driving connections between one of said first guide sprockets and one of said second guide sprockets for driving the latter, a releasable braking means holding said guide member in a given position of adjustment relative to said supporting member and second releasable braking means for holding one of said guide sprockets against rotation to thereby restrain both of said chains from circulating about said respective sprockets so that upon releasing said first named releasable braking means and operation of said motor said guide member moves relative to said supporting member while said drilling implement remains stationary relative to said guide member.

24. In a drilling machine the combination comprising a supporting member, a guide member carried by said supporting member and movable longitudinally relative to said supporting member, a drilling implement carried by said guide member and movable longitudinally relative to said guide member, abutment means at the front end of said guide member for engaging the face of the work to be drilled, a motor mounted on said supporting member, a drive sprocket carried by said supporting member and arranged to be driven by said motor, guide sprockets mounted on said guide member, a chain engaged by said drive sprocket and guided for circulation around said guide sprockets so that said chain circulates relative to said guide member, means connecting said chain to said drilling implement so that upon circulation of said chain around said guide sprockets said drilling implement moves longitudinally relative to said guide member, means for moving said guide member forwardly relative to said supporting member to bring said abutment means against the working face, and means for constantly urging said abutment means forwardly to maintain said abutment means firmly against the working face while said drilling implement moves forwardly relative to said guide member during the drilling operation.

25. In a drilling machine the combination comprising a supporting member, a guide member carried by said supporting member and movable longitudinally relative to said supporting member, a drilling implement including a rotary auger carried by said guide member and movable longitudinally relative to said guide member, abutment means at the front end of said guide member for engaging the face of the work to be drilled, a first motor mounted on said supporting member, a drive sprocket carried by said supporting member and arranged to be driven by said first motor, guide sprockets mounted on said guide member, a chain engaged by said drive sprocket and guided for circulation around said guide sprockets so that said chain circulates relative to said guide member, means connecting said drilling implement to said chain so that upon circulation of said chain relative to said guide member said drilling implement moves longitudinally relative to said guide member, means for moving said guide member forwardly relative to said supporting member to bring said abutment means against

the working face, means for constantly urging said abutment means forwardly to maintain said abutment means firmly against the working face while said drilling implement moves forwardly relative to said guide member during the drilling operation, and a second motor associated with said drilling implement and arranged to rotate said auger.

26. In a drilling machine the combination comprising a supporting member, a guide member carried by said supporting member and movable longitudinally relative to said supporting member, a drilling implement carried by said guide member and movable longitudinally relative to said guide member, abutment means at the front end of said guide member for engaging the face of the work to be drilled, a motor mounted on said supporting member, a drive sprocket carried by said supporting member and arranged to be driven by said motor, guide sprockets mounted on said guide member, a chain engaged by said drive sprocket and guided for circulation around said guide sprockets so that said chain circulates relative to said guide member, means connecting said chain to said drilling implement so that upon circulation of said chain around said guide sprockets said drilling implement moves longitudinally relative to said guide member, means to restrain movement of said drilling implement relative to said guide member so that upon energization of said motor said guide member moves longitudinally relative to said supporting member to bring said abutment means against the working face, and means for constantly urging said abutment means forwardly to maintain said abutment means firmly against the working face while said drilling implement moves forwardly relative to said guide member during the drilling operation.

27. In a drilling machine the combination comprising a supporting member, a guide member carried by said supporting member and movable longitudinally relative to said supporting member, a drilling implement carried by said guide member and movable longitudinally relative to said guide member, abutment means at the front end of said guide member for engaging the face of the work to be drilled, a motor mounted on said supporting member, a drive sprocket carried by said supporting member and arranged to be driven by said motor, guide sprockets mounted on said guide member, a chain engaged by said drive sprocket and guided for circulation around said guide sprockets so that said chain circulates relative to said guide member, means connecting said chain to said drilling implement so that upon circulation of said chain around said guide sprockets said drilling implement moves longitudinally relative to said guide member, locking means adapted to lock one of said guide sprockets to prevent circulation of said chain therearound so that upon energization of said motor said guide member moves longitudinally relative to said supporting member while said drilling implement remains stationary relative to said guide member to bring said abutment means against the working face, and means for constantly urging said abutment means forwardly to maintain said abutment means firmly against the working face while said drilling implement moves forwardly relative to said guide member during the drilling operation.

28. In a drilling machine, the combination comprising an elongated tubular guide member, a carriage movable longitudinally along said guide member, a rotary auger drilling implement rotatably mounted at its rear end on said carriage and extending longitudinally centrally within said tubular guide member, rotating means including a rotating element at the front end of said guide frame for engaging and driving said drilling implement, and an intermediate guide secured within the bore of said tubular guide member and having a central opening and a communicating lateral opening, the walls of said central opening partially surrounding the drilling implement to guide the latter, and said central and lateral openings providing a passageway through said guide

through which said carriage may pass as said carriage moves longitudinally along said guide member.

29. In a drilling machine the combination comprising a guide member, a drill carriage movable longitudinally along said guide member, a rotary auger drilling implement rotatably mounted at its rear end on said drill carriage and extending longitudinally of said guide member, said guide member having a front centralizer at its front end for guiding the forward portion of said auger, an intermediate centralizer mounted on said guide member between said drill carriage and said front centralizer, said intermediate centralizer being movable longitudinally relative to said guide member, and drive means arranged to move said intermediate centralizer relative to said guide member so that said intermediate centralizer is maintained in a position equidistant to both said drill carriage and said front centralizer irrespective of the longitudinal position of said drill carriage on said guide member.

30. In a drilling machine the combination comprising a guide member, a drill carriage movable longitudinally along said guide member, a rotary auger drilling implement rotatably mounted at its rear end on said drill carriage and extending longitudinally of said guide member, said guide member having a front centralizer at its front end for guiding the forward portion of said auger, an intermediate centralizer mounted on said guide member between said drill carriage and said front centralizer, said intermediate centralizer being movable longitudinally relative to said guide member, first drive means to move said drill carriage relative to said guide member, second drive means to move said intermediate centralizer relative to said guide member, and means connecting said first drive means to said second drive means so that said intermediate centralizer is maintained in a position equidistant to both said drill carriage and said front centralizer irrespective of the longitudinal position of said drill carriage on said guide member.
